RACK STRUCTURE

Donald J. McIntosh and Robert W. Crane, Detroit, Mich., assignors to McIntosh Stamping Corporation, Detroit, Mich., a corporation of Michigan

Application December 15, 1955, Serial No. 553,267

17 Claims. (Cl. 214—10.5)

This invention relates to a rack facilitating the storing of containers in stacked relation.

The invention can be used for stacking various kinds of pallets, crates, boxes and the like. An exemplary application is in stacking boxes of a type used for temporarily storing, handling and shipping industrial scrap metal. These boxes are lightly constructed for economical reasons and are not strong enough to support one another in stacked relation when filled with scrap metal. Still, it is desirable to stack the boxes to save floor space in a storage area or in a vehicle.

An object of this invention is to provide a simple, inexpensive rack structure enabling such containers to be stacked on one another and which can be rapidly and conveniently erected and dismantled to form stacks of various numbers of boxes.

The invention generally contemplates a pair of uprights formed of detachable sections spaced apart by detachable cross bars. The uprights extend adjacent the sides of the stack boxes, and the cross bars are arranged to support the central portions only of the boxes so that edge portions thereof engage each other to provide frictional lateral stability for the stack. One form of the invention is shown in the accompanying drawings.

Fig. 1 is a perspective view of a rack according to this invention in use.

Fig. 2 is a perspective view of a cross bar component separate from the rest of the rack structure.

Fig. 3 is a perspective view of an upright component separate from the rest of the rack structure.

Fig. 4 is an enlarged, generally elevational view illustrating engagement of the rack components with parts broken away and parts shown in phantom to illustrate structure.

Fig. 5 is a perspective view of a box separate from the rack structure.

Fig. 6 is a generally diagrammatic side elevation illustrating a box and rack structure carried by a lift truck.

Fig. 7 is an enlarged, fragmentary, partly diagrammatic view illustrating the relation between a box, a rack, and lift-truck fork.

Shown in Fig. 1 is a group of boxes 10 supported in stacked relation by a rack 11 constructed according to this invention. The rack structure includes a number of preferably identical upright sections 12 (Fig. 3) having a pair of legs 13 secured in parallel, spaced-apart relation by rungs 14 and 15 welded thereto as at 16. Each leg has a lower end portion 18 and has a lug 19 welded thereto adjacent its upper end 20. Lower rung 15 has end portions 21 extending laterally outwardly of legs 13 for a purpose to be described.

The rack structure also includes a number of preferably identical horizontal supports 25 each having a cross bar 26 with a tubular perpendicular sleeve 27 at each end. Sleeves 27 have open top ends 28 and open lower ends 29 and are dimensioned to fit slidably around the end portions of upright legs 13. The length of sleeves

2

27 is preferably about twice the length of upper portions 20 of legs 13 above lugs 19.

Each box 10 has sides 32 formed of a relatively lightweight material such as tin, wooden sheathing and is shown as being reinforced by wire bands 33. Box 10 has a top 34 and a bottom 35 which is normally supported by a number of blocks or feet 36 which in turn rest on parallel skids 37. Legs 13 of the upright members have the same height as boxes 10.

To form a stack of boxes 10, one box is positioned on the floor of a vehicle or storage space at the location where the stack is to be erected. A pair of upright sections 12 are positioned adjacent opposite sides of the box, and a pair of supports 25 are secured across the top of the box by sliding lower ends 29 of sleeves 27 over upper ends 20 of legs 13 so that the lower sleeve ends rest in load-bearing relation on lugs 19. A second box 10 is stacked on the first box with its bottom 35 resting on cross bars 26. The top of the cross bar is spaced above the top 34 of the lower box so that skids 37 of the upper box contact top 34 of the lower box. The weight of the upper box on cross bars 26 is transmitted to legs 13 of the upright section through sleeves 27 and lugs 19.

25 A second rack tier is erected on the first by inserting lower ends 18 of the legs of a second pair of uprights into open upper ends 28 of sleeves 27 so that they abut in load-bearing relation against upper ends 20 of the lower set of legs 13. A second tier of cross bars 26 is attached to the uprights and a third box 10 may be stacked on the lower boxes by positioning it on the second tier of cross bars 26 in the manner described. The weight of this box is transmitted to the column of vertically abutted legs 13 through the sleeves 27 and lugs 19 of the upper rack tier. Additional boxes may be placed on the stack by erecting additional tiers of rack sections and positioning boxes thereon as described.

30 Cross bars 26 straddle the central row of feet 36 and support only a generally central portion of box 10. When the boxes in a stack are loaded, their unsupported side portions tend to sag and bear upon the top of the next lower box in the stack. Each box provides partial support for the boxes above it. The frictional engagement of skids 37 against subjacent box tops 34 provides adequate lateral stability for a stack of boxes. The central, partial support provided by the rack structure enables a number of relatively weak, heavily loaded boxes to be stacked upon one another, where without such support the lower boxes would collapse.

35 A stack of boxes and the rack structure may be partly or completely dismantled by merely lifting boxes off of the top of a stack and disengaging upper and lower end portions 18 and 20 of the upright legs from sleeves 27 on the cross members. The rack is constructed to facilitate forming and dismantling of stacks of boxes by the use of lift trucks 40 as illustrated in Figs. 6 and 7. Truck 40 has forks 41 which can be elevated and lowered on an element 42, the forks being spaced apart to straddle the inner row of feet 36 of a box. When the forks are inserted in the vertical space between two boxes and lifted upwardly, they engage outward extensions 21 of the lower rung 15 on upright sections 12. The rack structure together with the box is thereby lifted off of the stack. A number of boxes and their corresponding tiers of racks may be lifted off or added to the stack at one time if desired.

40 Rungs 14 and 15 not only serve to secure legs 13 in spaced relation but also form a ladder which may be safely climbed for inspection of the contents of the boxes and the like. The rungs in an erected rack are generally equally vertically spaced. Upright sections 12 and cross

members 25 are relatively flat so that they can be conveniently stored when not in use. The respective elements are identical to facilitate inexpensive manufacture and are formed preferably of metal tubing so that they are lightweight and easy to handle.

The invention facilitates forming stacks of boxes at any desired location without the necessity of leaving space consuming aisleway between stacks to facilitate subsequent handling of the boxes. The rack structure can be erected and dismantled with very little more effort and time than is required to stack boxes themselves.

We claim:

1. A rack structure facilitating the stacking of holders for storing materials, said rack structure comprising, upright support means, lateral support means secured to said upright support means in load-bearing relation so that vertical load imposed on said lateral support means is transmitted to and supported by said upright support means, said upright support means being arranged to be positioned adjacent a holder with which said rack is adapted to be used with said lateral support means extending over the top of the holder, said lateral support means being adapted to engage and provide vertical support for a portion of the bottom of a like holder placed in stacked relation over the first holder while leaving other portions thereof unsupported, said lateral support means being vertically positioned on said upright support means so that the unsupported bottom portion of the upper holder engages upper portions of the lower holder, whereby to provide frictional lateral stability for the stack of holders.

2. A rack structure facilitating the stacking of containers having generally form retaining walls adequate to contain goods but inadequate of themselves to resist buckling under the weight of other loaded containers stacked thereon, said rack structure comprising, a plurality of upright members, a cross member secured to said upright members in load-bearing relation, said upright members being arranged to be positioned upright generally adjacent opposite walls of a container with which said rack is adapted to be used with said cross member extending over the top of the container at a location spaced from edge portions of the container, said cross member being adapted to supportingly engage a portion of the bottom of a like container placed in stacked relation over the first container, said cross member being vertically positioned on said upright members so that unsupported bottom portions of the upper container engage upper portions of the lower container whereby to provide frictional lateral stability for the stack of containers.

3. A rack structure facilitating the stacking of containers having generally form retaining walls adequate to contain goods but inadequate of themselves to resist buckling under the weight of other loaded containers stacked thereon, said rack structure comprising a plurality of upright members, a plurality of cross members, each upright member including a plurality of column elements and means securing the column elements in generally parallel, spaced apart relation, attachment means detachably securing a cross member to each of said column elements in load-bearing relation, said column elements being adapted to be positioned upright generally adjacent opposite side walls of a container with which said rack is adapted to be used and to support said cross members above the container, each of said cross members being adapted to supportingly engage a like container placed in stacked relation over the first container, the width across said cross members being relatively smaller than the width of the container with which said rack is adapted to be used so that a cross member supports a generally central portion of an upper container leaving edge portions thereof unsupported, said cross members being vertically positioned on said upright members so that the unsupported edge portions of an

upper container engage upper portions of a lower container to provide frictional lateral stability for a stack of containers, said attachment means detachably securing the column elements of certain of said upright members together in vertical load-transmitting relation, whereby to form racks for partially supporting stacks of selected numbers of containers.

4. A rack structure facilitating the stacking of containers having generally form retaining walls adequate to contain goods but inadequate of themselves to resist buckling under the weight of other loaded containers stacked thereon, said rack structure comprising, a plurality of upright members, a plurality of cross members, each upright member including a plurality of column elements, said column elements in each upright member being secured in generally parallel, spaced apart relation by rung means, attachment means detachably securing a cross member to each of said column elements in load-bearing relation, said column elements being adapted to be positioned upright generally adjacent opposite side walls of a container with which said rack is adapted to be used and to support said cross members above the container, each of said cross members being adapted to supportingly engage a like container placed in stacked relation over the first container, the width across said cross members being relatively smaller than the width of the containers with which said rack is adapted to be used so that a cross member supports generally the central portion of an upper container leaving edge portions thereof unsupported, said cross members being vertically positioned on said upright members so that the unsupported edge portions of an upper container engage upper portions of a lower container to provide frictional lateral stability for a stack of containers, said attachment means detachably securing the column elements of certain of said upright members together with said column elements thereof in vertical abutment, whereby to form racks for partially supporting stacks of selected members of containers, said rung means cooperating to form ladder means to facilitate climbing a stack for inspection purposes and the like.

5. A rack structure facilitating the stacking of containers having generally form retaining walls adequate to contain goods but inadequate of themselves to resist buckling under the weight of other loaded containers stacked thereon, said rack structure comprising, a plurality of upright members, a plurality of cross bars, each upright member including a pair of column elements secured in generally parallel, spaced apart relation by spaced apart rungs, attachment means detachably securing the end portions of two of said cross bars to the top portions of the column elements of two of said upright members, said cross bars extending generally parallel to each other and being in load-bearing relation with said upright members, said column elements being adapted to support said cross bars above a container with which said rack is adapted to be used and being spaced apart by said cross bars for extending upright generally adjacent opposite side walls of the container, said cross bars being adapted to supportingly engage a like container placed in stacked relation over the first container, the distance between said cross bars being relatively smaller than the width of the containers so that said cross bars support a generally central portion of a container leaving edge portions thereof unsupported, said cross bars being vertically positioned on said column elements so that the unsupported portions of a container engage upper portions of a lower container to provide frictional lateral stability for a stack of containers, said attachment means detachably securing the column elements of certain of said upright members together with said column elements in vertical abutment, whereby to form racks for partially supporting stacks of selected numbers of containers, said rungs cooperating to form

ladders on opposite sides of a stack to facilitate climbing thereof for inspection purposes and the like.

6. The combination defined in claim 5 wherein said attachment means includes a tubular element at each end of said cross bar, said tubular element engaging vertically abutted column elements for securing them together, each column element having a projection thereon supporting said tubular element and a load thereon.

7. Structure for storing items comprising, a plurality of holders for items to be stored, load-bearing upright means adapted to rest on a supporting surface, a plurality of vertically spaced lateral members secured to said upright means in load-bearing relation so that vertical load imposed on said lateral members is transmitted to and supported by said upright means, said holders being arranged to be selectively placed on said lateral members and on a supporting surface beneath the lower of said lateral members, said lateral members being constructed and arranged to engage and provide vertical support for a predetermined portion of the bottom of a holder placed thereon while leaving other portions of the holder unsupported, each holder engaging an adjacent holder in a stack at said unsupported portions whereby to provide frictional lateral stability for a stack of holders.

8. A device for storing items comprising, a plurality of generally form retaining holders for items to be stored, a plurality of load-bearing upright members adapted to rest on a supporting surface, each upright member being formed of a plurality of detachable sections, a plurality of cross members, means detachably securing said cross members to said upright members at the junctures of said sections, means on said holders forming supporting feet, said holders being arranged to be selectively placed on said cross members with said cross members extending between said feet, said holders being also arranged to be placed beneath the lower of said cross members with said feet resting on a supporting surface, said cross members being constructed and arranged to supportingly engage a generally central portion of a holder placed thereon leaving other portions of the holder unsupported, said feet being disposed at said unsupported portions and engaging an adjacent holder in a stack to provide frictional lateral stability for a stack of holders.

9. The combination defined in claim 8 wherein the height of each of said sections is substantially the same as the height of each of said holders.

10. Structure for storing items comprising, a plurality of generally form retaining holders for items to be stored, a plurality of upright sections, said sections including a pair of column elements secured in generally parallel spaced apart relation by a plurality of rung elements, a plurality of cross bars, means detachably securing said sections together with said column elements in vertical abutment to form a plurality of load-bearing uprights, said means detachably securing said cross bars to said uprights at the junctures of said column elements, said uprights being arranged and constructed to rest on a supporting surface adjacent side portions of a holder element also resting on the supporting surface with some of said cross bars extending over the top of said holder, said holders being arranged to be selectively placed on said cross bars, said cross bars being constructed and arranged to supportingly engage a generally central portion of the bottom of a holder placed thereon leaving edge portions of said holder unsupported, downwardly projecting means forming feet on each holder engaging the next lower holder in a stack whereby to provide frictional lateral stability for a stack of holders, said rungs cooperating to form ladders at the sides of a stack to facilitate climbing the stack for inspection purposes and the like.

11. Structure for storing items comprising a plurality of generally form retaining holders for items to be stored, a plurality of upright sections, said sections including a pair of column elements secured in generally

parallel spaced apart relation by a plurality of rung elements, a plurality of cross bars, each cross bar having at each end a sleeve element extending generally perpendicularly thereto, each sleeve element being open at both ends, said sleeve elements slidably detachably engaging the top portions of some of said column elements, each of said sleeve elements slidably detachably engaging the bottom end portions of the other of said column elements to secure said sections together with the column elements thereof vertically abutted to form a plurality of spaced apart load-bearing uprights, said uprights being arranged and constructed to rest on a supporting surface adjacent side portions of a holder element also resting on the supporting surface with some of said cross bars extending over the top of said holder, said holders being arranged to be selectively placed on said cross bars, said cross bars being constructed and arranged to supportingly engage a generally central portion of the bottom of a holder placed thereon leaving edge portions of said holder unsupported, downwardly projecting means forming feet on each holder engaging the next lower holder in a stack whereby to provide frictional lateral stability for a stack of holders, said rungs cooperating to form ladders at the sides of a stack to facilitate climbing the stack for inspection purposes and the like.

12. The combination defined in claim 11 wherein the bottom of each support and said feet thereon are adapted to be lifted by elements inserted under said support, the lower of said rungs on each of said sections being positioned generally adjacent a support bottom and being adapted for engagement by lifting elements inserted beneath a support so that when a support is lifted off a stack the corresponding cross bars and upright sections are lifted with it.

13. Structure for storing items comprising, a plurality of holders for items to be stored, means providing a plurality of generally horizontally extending members spaced vertically in load bearing relation on upright support means so that vertical load imposed on said members is transmitted to and supported by said upright support means, said holders being arranged to be placed on said members one above the other, said members being constructed and arranged to engage and provide vertical support for a portion of a holder placed thereon while leaving other portions of the holder unsupported, each holder engaging an adjacent holder at said unsupported portions whereby to provide lateral stability for a stack of holders.

14. Structure for storing items comprising, a plurality of holders for items to be stored, a plurality of load bearing upright members adapted to rest on a supporting surface, a plurality of vertically spaced load bearing cross members extending between said upright members so that vertical load imposed on said cross members is transmitted to and supported by said upright members, said holders being arranged to be placed selectively on the supporting surface and said cross members one above the other to form a stack, said cross members being constructed and arranged to engage and provide vertical support for a portion of a holder placed thereon while leaving other portions of the holder unsupported, each holder engaging an adjacent holder in a stack at said unsupported portions whereby to provide lateral stability for a stack of said holders.

15. A method of storing goods which comprises, providing a plurality of containers having generally form retaining walls adequate to contain goods but inadequate of themselves to resist buckling under the weight of other containers in loaded condition stacked thereon, placing the goods in said containers, arranging said containers one above the other in a stack, providing vertical support for portions of said containers and leaving other portions thereof unsupported, and leaving the unsupported portions of adjacent containers in the stack free to interengage to provide lateral stability for the stack.

16. A method of storing goods which comprises, pro-

viding a plurality of containers having generally form retaining walls adequate to contain goods but inadequate of themselves to resist buckling under the weight of other containers in loaded condition stacked thereon, placing the goods in said containers, arranging said containers one above the other in a stack, providing vertical support for central portions of said containers and leaving edge portions thereof unsupported, and leaving the unsupported edge portions of adjacent containers in the stack free to interengage to provide lateral stability for the stack.

17. Structure for storing items comprising, a plurality of containers for the items to be stored, each container having a bottom wall and side walls, said side walls being adequate to contain said items but being inadequate of themselves to resist buckling under the weight of other containers in loaded condition stacked thereon, and a rack structure facilitating the stacking of said containers which includes upright support means, lateral support means secured to said upright support means in load bearing relation so that vertical load imposed on said lateral support means is transmitted to and supported by said upright support means, said containers being posi-

tionable adjacent said upright support means with said lateral support means extending over the top of said container, said lateral support means being adapted to engage and provide vertical support for a portion of the bottom of a like container placed in stacked relation over the first mentioned container while leaving other portions thereof unsupported, said lateral support means being vertically positioned on said upright support means so that the unsupported bottom portion of the upper 10 container engages upper portions of the lower container, whereby to provide frictional lateral stability for the stack of containers.
